FOLDING TOILET

John W. Jarrett, Russell L. Tangeman, and Max B. Schmidt, Dayton, Ohio, assignors, by mesne assignments, to Loeffelholz Company, Milwaukee, Wis., a corporation of Wisconsin

Application July 21, 1947, Serial No. 762,474

21 Claims. (Cl. 4-10)

1

This invention relates to folding toilet assemblies of the type adapted for such use where compactness and conservation of space is desired.

One of the principal objects of the invention is to provide a complete folding toilet unit including in a single supporting frame a lavatory and a hopper each mounted for ready movement between an open position for use and a closed position wherein they occupy minimum space, a mirror mounted above the lavatory, and light sources mounted adjacent the mirror for illuminating the face of the user of the mirror.

Another object is to provide a power operated mechanism for effecting movement of a folding toilet hopper between an open position ready for use and a closed position under selective manual controls.

Still another object is to provide a folding toilet unit including a hopper movable between open and closed positions and having cover panels arranged to move in response to movement of the hopper to positions fully enclosing and protecting the hopper and its operating mechanism, maintaining a clean, sanitary condition and a smoothly finished construction in all positions.

An additional object is to provide a fluid pressure mechanism for effecting the opening and closing movement of a folding toilet unit, and particularly to provide such an arrangement wherein the fluid pressure mechanism is operated by water and can thus be readily connected to a source of water under pressure such as the water supply system of a railroad car or other vehicle or building.

A further object is to provide a folding toilet wherein movement of the hopper between its open and closed positions is effected by a hydraulic cylinder or cylinders and wherein the waste water from the cylinders is conducted to the hopper to provide a wet bowl when the hopper is in open position.

It is also an object of the invention to provide a folding toilet including a hopper movable between open and closed positions and having an actuating member for initiating flushing of the hopper which is made readily accessible for operation when the hopper is in open position and which is automatically withdrawn from its operating position to an inaccessible and inoperative position when the hopper is moved to its closed position.

Still another object is to provide a toilet hopper having a flushing system constructed and arranged to give a broad flat jet of flushing liquid across the bottom of the hopper from front to

2

back to sweep the contents thereof into the discharge outlet and thus to assure effective and thorough flushing.

A further object is to provide a toilet wherein the discharge outlet of the hopper is normally substantially closed to prevent return air currents from entering the hopper but which opens automatically when the hopper is flushed and remains open during flushing.

10 Another object is to provide a folding toilet unit including a hopper movable between open and closed positions and having cover panels arranged for movement in response to movement of the hopper to cover over the edges of the 15 hopper when the hopper is closed and provide a smoothly finished appearance facilitating the cleaning of the entire unit.

10 Another object is to provide a hopper for a folding toilet having a simple and effective flushing or shower ring which is so constructed and mounted within the hopper as to minimize the time and labor required for its removal for servicing or replacement.

25 An additional object is to provide an illuminated mirror for use in a toilet unit of such construction and arrangement that the face of the user is fully and effectively illuminated without producing a glare in the user's eyes.

30 Still another object is to provide a mirror unit for use in a folding toilet or other installation which includes light sources so positioned and arranged as to be out of the normal range of vision of the user but at the same time to illuminate the user's face effectively for shaving or other purposes when the user is in normal position in front of the mirror.

35 A still further object is to provide an illuminated mirror unit having light sources mounted only at the top and bottom of the mirror frame 40 and forwardly of the plane of the mirror in predetermined positions to illuminate the face of the user while avoiding glare and objectionable light in the eyes of the user.

45 Other objects and advantages of the invention will be apparent from the following description, the accompanying drawings and the appended claims.

50 In the drawings, in which like characters of reference designate like parts throughout— Fig. 1 is a view in perspective illustrating a complete folding toilet unit in accordance with the invention;

55 Fig. 2 is a view of the unit of Fig. 1, the view being partly in side elevation and partly broken

away and in section to illustrate details of internal construction and arrangement;

Fig. 3 is a partial front view in perspective of the unit showing the hopper closed and with certain of the panels removed to illustrate internal construction;

Fig. 4 is a partial front view in perspective showing the hopper open and ready for use;

Fig. 5 is a view in perspective showing the side of another folding toilet unit in accordance with the invention, the hopper being shown in open position and certain of the side paneling being removed to show internal construction;

Fig. 6 is a view in perspective of the back of the unit, with parts of the frame being broken away to show the internal construction and arrangement;

Figs. 7 and 8 are side elevational views of the lower part of the unit showing the hopper in closed and open positions, respectively, and with parts removed or broken away to show internal construction;

Fig. 9 is a fragmentary view in perspective illustrating a part of the flushing mechanism of the hopper;

Fig. 10 is a top plan view of the flushing valve and the lever and treadle for operating the flushing valve;

Fig. 11 is a view of the flushing mechanism taken partly in side elevation and partly in vertical section on the line 11—11 of Fig. 10;

Fig. 12 is a view partly in vertical section and partly in side elevation through the hopper to illustrate details of the flushing and discharge mechanisms;

Fig. 13 is a top view of the hopper with parts broken away to illustrate the flushing system;

Fig. 14 is an enlarged view partly in side elevation and partly broken away and in vertical section through the discharge outlet of the hopper and the valve controlling this outlet;

Fig. 15 is an enlarged detailed view of the flushing jet of the hopper, the view being taken in section substantially on the line 15—15 of Fig. 13;

Fig. 16 is a diagrammatic view illustrating electric means for operating the valve controlling the discharge outlet of the hopper;

Fig. 17 is a view similar to Fig. 16 illustrating hydraulic means for operating the valve controlling the discharge outlet of the hopper;

Fig. 18 is an enlarged detail view partly in elevation and partly broken away and in vertical section showing the joint between the main drain pipe and the connecting pipe from the discharge outlet of the hopper;

Fig. 19 is a fragmentary view of the lavatory, partly broken away to show the latching mechanism therefor;

Fig. 20 is a fragmentary view partly in side elevation and partly in section on the line 20—20 of Fig. 19;

Fig. 21 is a diagram illustrating a piping arrangement for use in the unit of Fig. 1; and

Fig. 22 is a diagram illustrating a modified piping arrangement in accordance with the invention.

The invention provides a complete folding toilet unit having substantial advantages for use in many installations where it is desired to conserve space, typical examples being railroad cars, airplanes, and other vehicles as well as in business or living quarters where floor space is limited. The unit includes both a hopper and a lavatory each mounted in a common frame for movement between an open position ready for use

and a closed position wherein it is folded into the frame and occupies minimum space. To add to the visual appearance of the unit, panels are provided covering the spaces above and below the hopper, these panels being so mounted in the frame as to move into and out of their desired covering positions in response to the movement of the hopper between its open and closed positions and to impart a smooth and substantially unbroken appearance to the unit when the hopper is closed, facilitating the keeping of the entire unit in a clean and sanitary condition.

An operating member such as a foot treadle is provided for flushing of the hopper, and it is so constructed and arranged that when the hopper is closed, it retracts from its advanced convenient operating position to a position within the frame wherein it is substantially inaccessible and out of the way. In addition, the operating connection between this treadle and the flushing system is such that the treadle can operate to initiate flushing of the hopper only when it is in its advanced position, thus effectively preventing accidental flushing of the hopper when it is not fully lowered to its operative position.

The flushing system also includes a valve such as a flapper valve for controlling the discharge outlet of the hopper, and this valve is so connected with the flushing mechanism that it opens in response to actuation of the flushing mechanism but remains closed at other times to prevent the passage to and from the hopper of air currents such as may be caused by motion of a train or other vehicle wherein the unit is installed.

Provision is made in accordance with the invention for power operation of the hopper in moving between its open and closed positions. Thus the hopper can be caused to open or close by simple manipulation of a button, valve or other control member. Highly satisfactory results have been obtained by the use of hydraulic operating means for the hopper such as one or more double-acting hydraulic cylinders. Since the toilet unit normally includes connections to a water supply for flushing and for the lavatory, it is a simple matter to make the proper connections for supplying water to operate the hopper cylinders. In addition, the cylinders may be connected with the flushing system in such manner that when pressure is applied to one side of the cylinder or cylinders to cause the hopper to open, the waste water from the opposite side of each cylinder is caused to flow into the hopper to provide a wet bowl preparatory to use.

The invention also provides in the toilet unit a mirror mounted in the frame above the lavatory and equipped with built-in light sources arranged to give highly effective illumination for the face of the user while at the same time shielding the user's eyes from direct glare. It has been determined that when a person is looking substantially straight ahead, the angular range of vision of the eyes is substantially greater in a horizontal plane than in a vertical plane. That is to say, even though the eyes are directed straight ahead, they will still be able to perceive objects to the right or left over a substantial angular range, but the corresponding range of perception with respect to objects above or below the direct line of level vision is considerably more restricted. In accordance with the invention, the light sources for the mirror are mounted only above and below the mirror and in predetermined positions forwardly of the plane thereof such

that they will lie respectively above and below the range of level vision of the user of the mirror both as viewed directly and by reflection in the mirror. This arrangement is practicable even though the light sources would lie within the horizontal range of the user's vision if they were positioned at the same distance apart at either side of the mirror. In addition, these light sources are provided with means for directing the light therefrom forwardly of the mirror and respectively downwardly and upwardly at such angles to the horizontal as to produce effective illumination on the face of the user without striking the user's eyes in such manner as to cause glare.

Referring to the drawings, which illustrate preferred embodiments of the present invention, Figs. 1 and 2 show a complete folding toilet unit comprising a frame which is indicated generally at 25 and includes a pair of front channel bars 26 and a pair of rear channel bars 27, these channels being integral or secured together as indicated by the front and rear angle bars 28 and side angle bars 29 at the bottom of the frame. In the frame 25 are mounted a lavatory 30, a hopper indicated generally at 33, and a mirror 35 positioned above the lavatory and provided with upper and lower light sources indicated generally at 36 and 37, respectively. Fig. 1 shows the unit with both the lavatory and hopper in their closed positions, in which they fold into the frame and into substantially vertical positions occupying minimum space horizontally. Fig. 2 shows in full lines the positions of the hopper and lavatory when open, in which positions they extend substantially horizontally from the frame, and also shows in dotted lines the positions of the lavatory and hopper when closed as illustrated in Fig. 1.

The construction and operation of the lavatory is shown in somewhat more detail in Figs. 2 and 6. Referring to Fig. 2, the lavatory is mounted for swinging movement about a horizontal pivotal mounting 40 in the frame, and it extends rearwardly at 41 beyond this pivotal mounting and under a faucet fixture 42, one of the operating levers for this fixture being shown at 43. Stop means such as one or more rubber buttons or bumpers 44 are positioned on the underside of the fixture 42 to engage the lavatory portion 41 and thus to stop the lavatory in the desired horizontal position as shown in Fig. 2. Another stop, shown as a cushion 45 of rubber or like material, is mounted in the frame as shown in Figs. 1 and 2 to engage the front rim of the lavatory when it is closed. Releasable latches 46 are provided at each side of the lavatory and are adapted to engage within the frame to hold the lavatory in closed position, and a handle 47 is provided for controlling these latches as described in detail in connection with Figs. 19 and 20. When the lavatory is closed, as shown in Figs. 1 and 5, its bottom will be substantially flush with the panel 48 fixed across the front of the unit frame.

The piping for conveying water to and from the lavatory is shown in Figs. 2, 5 and 6. Connections for hot and cold water for the faucet fixture 42 are indicated at 49 and 50, respectively, in Figs. 2 and 5, and it will be understood that they provide for connections to the regular water supply of a railroad car or other vehicle or building in which the unit is installed.

A tank 51 open at the top thereof is mounted in the frame 25 as shown in Fig. 2 in such manner that the back portion 41 of the lavatory enters

therein when the lavatory is closed, thus dumping into this tank 51 any water that is in the lavatory. From the tank 51, the water passes through pipe 52 to a trap coupling 53 (Fig. 6) from which it is conducted through a connecting pipe 54 to the main drain or sewer pipe 55 of the unit. The trap coupling 53 is provided with a removable plug 57 for clean-out purposes, and also with a supplemental connecting line 58 (Fig. 6) to the main drain, this line being controlled by a petcock 59 and providing for draining liquid from the trap 53 before removal of plug 57 for clean-out purposes. It should also be noted that the unit may be constructed without the mirror, in which case the top of the frame 25 is finished over above the lavatory as shown at 60 in Fig. 5.

The general construction of the hopper is best seen in Figs. 1 to 8 and 12 to 14, and as shown, it includes a bowl having a relatively flat bottom portion 65 and upwardly curved side portions 66. The bowl bottom 65 slopes upwardly from front to back when the hopper is open, as illustrated particularly in Figs. 12 and 14, and a discharge outlet 67 is formed at the back of the bowl. As shown in Figs. 13 and 14, a bracket frame 68 extends across the back of hopper bowl and is welded or otherwise secured thereto. A curved connecting pipe 70 leads from the discharge outlet 67 and telescopes into the main drain pipe 55 to provide for the necessary movement of the hopper relative to pipe 55 when opening and closing. As shown in Fig. 14, the pipe 70 is flanged and bolted to the bracket frame 68 at 71, a suitable gasket 72 being provided to insure a tight connection.

The top of the hopper bowl is formed by an annular tray 75, which is welded or otherwise secured to the bowl as indicated at 76 (Fig. 3). This tray includes a downwardly extending outer flange portion 77 surrounding the front and sides of the bowl as shown in Figs. 4 and 12 and an upwardly inclined rear edge 78. A seat 80 is provided with a hinged connection 81 to the back of the tray 75 for swinging movement as shown in Fig. 5, and this seat is also provided with rubber bumper members 82 adapted to support the seat on hopper tray 75. The lower part of the bowl is enclosed by a skirt 85 shaped somewhat like a scoop which conceals the bowl and the flushing connection thereto.

The skirt 85 engages under the flanged portion 77 of tray 75 and may be bolted or otherwise removably secured thereto as indicated at 86 (Fig. 6) and provides a finished appearance to the unit when the hopper is closed, as illustrated in Fig. 1. A panel 88 is hingedly connected at 89 along the lower edge of skirt 85 to cover the space below the skirt when the hopper is closed. As shown in Figs. 2 and 4, this panel folds upwardly and retracts with the skirt when the hopper is open, but it advances when the hopper is closed to overhang the space below the skirt, in which position it combines with a panel 90 bolted or otherwise secured to the front pair of channel bars 26 of the frame, thus providing a smooth and finished appearance for the unit as shown in Fig. 1. Additional side panels 92 may be provided at the sides of the frame as shown in Fig. 1 to enclose the operating parts of the unit.

The structure for supporting the hopper in frame 25 is best seen in Figs. 3, 5 and 6, and it includes a pair of brackets 99 each of which is welded at 100 or otherwise secured to the hopper bowl and also to the bracket frame 68 at the back of the bowl. Each bracket 99 is provided

with a bearing 101 (Fig. 3) in which is journaled a stud or trunnion 102. Each stud 102 is mounted in a bearing 103 (Fig. 6) which is bolted between a pair of plates 104 which brace the corners of the frame 25. The brackets 99 are also provided with a brace 105 extending across the bottom of the bowl and preferably welded thereto at 106 for additional stiffening effect. This brace is adapted to engage a stop 107 (Fig. 3) at the front of the frame when the hopper is fully open, thus limiting opening movement of the hopper.

The flushing system for the hopper is best shown in Figs. 8, 12, 13, 15 and 21. Referring particularly to Figs. 12 and 15, a fixture 110 is welded at 109 to the bottom of the hopper bowl and provided with a connecting pipe 111 leading to a suitable supply of water under pressure for flushing. An angular plate 112 is welded at 113 along one edge to the fixture 110, and its opposite end extends through a slot 114 in the side of the hopper bowl and is welded to the bowl as at 115. As shown in Fig. 15, this plate 112 thus combines with the bottom of fixture 110 to form a narrow passage or jet 116 leading from the interior of the fixture 110 through slot 114 into the bowl and extending substantially across the flat bottom portion 65 of the bowl as shown in Fig. 13.

The jet opening 116 from fixture 110 provides for admitting to the hopper bowl a major proportion of the flushing liquid supplied to the fixture 110, and in addition a shower ring is provided for admitting at the top of the bowl a minor proportion of the flushing liquid. Referring to Figs. 8, 12, 13 and 21, the shower ring is composed of two sections of pipe 120 curved to fit within the upper part of the bowl under tray 75 and having spaced outlets 121. Each of these pipes 120 is provided with a coupling 122 which extends through a hole in the side of the bowl for connection with an additional pipe 123 connecting at 124 with the sides of the jet fixture 110. With this construction, either of the shower ring pipes 120 can be quickly and easily removed for repair or replacement by simply loosening the coupling 122 and withdrawing the pipe from the bowl, without the necessity of disconnecting or removing any other part of the hopper such as would be required if the shower ring were formed by a single curved pipe.

It will accordingly be seen that when water is supplied under pressure to the fixture 110 through pipe 111, the major proportion thereof will be directed through the jet passage 116 in a broad but relatively flat jet directed across the hopper bottom in such manner as to sweep the contents of the hopper towards the discharge outlet 67. At the same time, a minor proportion of the water will be introduced as a shower at the top of the hopper to wash down the sides of the bowl into the path of the main jet, thus providing for highly effective flushing. Water for flushing purposes is preferably initially supplied through a direct pipe connection 125 (Figs. 5, 6 and 21) from the main cold water supply, and a connection 126 is provided from this pipe to a normally closed flushing valve 127. A pipe 128 leads from the valve 127 to a vacuum breaker 129 of conventional construction, and a further pipe 130 leads from the vacuum breaker and connects with the pipe 111 through a swiveled coupling 131, this swiveled coupling being provided to allow for swinging movement of the hopper relative to the pipe 130 during opening or closing movement of the hopper. It will be noted that the pipe

75

125 is adapted to extend completely through the unit frame, thus providing for connecting a series of units to a common water supply.

The invention provides for power operation of the opening and closing movement of the hopper, and the drawings show double-acting hydraulic cylinders for effecting and controlling this movement. Referring particularly to Figs. 2, 5 and 6, two double-acting hydraulic cylinders 140 are pivotally connected at 141 to the angle iron 28 extending across the back of the unit between the rear pair of channel bars 27 of frame 25. The piston rods 145 from cylinders 140 are pivotally connected at 146 to the bracket frame 68 at the back of the hopper bowl. It will be seen that with this construction, when pressure fluid is admitted to the lower sides of the cylinders 140, the pistons therein will be forced upwardly and will accordingly cause opening movement of the hopper, the pivotal mountings of the cylinders 140 providing for the necessary swinging movement of the cylinders to follow the similar movement of the hopper. Conversely, when pressure fluid is admitted to the upper side of the cylinders 140, their pistons will be forced downwardly and will accordingly act to raise the hopper into its substantially vertical closed position.

The fluid for operating hydraulic cylinders 140 is supplied through a branch connection from the cold water line to the lavatory faucet, and additional connections are provided for conducting waste water discharged from the cylinders 140 to the hopper bowl to provide a preliminary flush or wet bowl when the hopper is first opened. Referring particularly to Figs. 6 and 21, a pipe 149 leads from the cold water side of the faucet fixture 42 to a four-way valve indicated generally at 150 and provided with a pair of control members such as push buttons 151 and 152. From the valve 150, one pipe 155 leads to a flexible hose 156 connecting through coupling 157 with a pipe 158 leading to the upper sides of the two cylinders 140, the flexible hose 156 being provided to allow for the movement of pipe 158 when the cylinders 140 swing as described. Another pipe 160 leads through a flexible hose 161 and coupling 162 to a pipe 163 connecting with the lower sides of the two cylinders 140. The fourth pipe 165 which leads from valve 150 connects at 166 with the pipe 128 which connects the flushing valve 127 with the vacuum breaker 129.

The valve 150 is shown as mounted in the front panel 47 of the frame, and the two control buttons 151 and 152 are preferably provided with suitable legends such as "Open" and "Close" as shown in Figs. 3 and 4. The arrangement within the valve is such that when the "Open" button 151 is actuated, it will connect the pipe 149 with the pipe 160 and simultaneously connect the pipe 155 with the pipe 165. When this occurs, it will be seen that line pressure from the cold water line 50 is applied at the lower sides of the cylinders 140, to force the pistons therein to rise and to cause the hopper to open. At the same time, since the upper sides of the cylinders will be connected through pipes 155 and 165 to the flushing line 128, this will cause the waste water displaced from the upper sides of the cylinders to be conducted through the vacuum breaker and through pipe 130, coupling 131 and pipe 111 into the jet fixture 110 and thence into the bowl. This will thus provide the desired relatively small

quantity of water to form a wet bowl in the open hopper preparatory to use.

When the "Close" button 152 of valve 150 is actuated, the converse operation will take place. Line pressure will be applied through pipes 149 and 155 to the upper sides of the cylinders 140, thus forcing the pistons therein downwardly to cause closing movement of the hopper. During this movement, the waste water from the lower sides of the cylinders will be similarly conducted to the flushing line and thence into the bowl, and from there it will drain downwardly to the main drain pipes as a result of the vertical position of the bowl when closed. It should also be noted that if the hopper is reused before closing and reopening, the desired quantity of water for the preliminary flush will be left over from the flushing operation as a result of the upwardly sloping construction of the bottom portion 65 of the bowl, as shown in Figs. 12 and 14, which will prevent all the flushing water from draining from the bowl. In order to insure that this water be perfectly clean, it is merely necessary to continue the flushing until the force of the jet has effectively cleaned the hopper. It will also be seen that when the hopper is finally closed, all water remaining therein will drain through the outlet 67 to leave the bowl dry.

In addition to the movable panel 88 below the hopper, other panels are mounted in the frame 25 for movement in response to opening and closing movement of the hopper between retracted positions and operative positions wherein they conceal the operating mechanism and give a finished appearance to the unit. Referring particularly to Figs. 2, 3, 4, 7 and 8, a panel 170 is pivotally mounted for swinging movement about a horizontal axis 171, as by means of brackets 169 secured to the frame just below the fixed panel 47. This panel 170 includes a portion 172 extending across the unit below the axis 171 which is adapted to be engaged by the top of the hopper seat 89 when the hopper closes, means such as rubber buttons 173 being provided to cushion the seat as shown in Fig. 4. The arrangement of this panel is such that when the hopper is closed, its seat 89 forces the panel to swing forward and downward into a position overhanging the cover tray 75 as shown in Figs. 1 and 7, in which position the front of panel 170 is substantially flush with frame panel 47, as shown, to impart a substantially unbroken appearance to the hopper. When the hopper starts to open, torsion springs 174 cause the panel portion 170 to spring upwardly about its pivot axis 171, as shown in Fig. 7, thus releasing the hopper to complete its opening movement, and the panel remains in this retracted position until it is returned to its closed position by contact between the hopper seat 89 and the rubber buttons 173 on panel portion 172 when the hopper closes.

Another panel is mounted within the frame for movement into a position concealing the space above and behind the hopper and the operating mechanism therein when the hopper opens. Referring particularly to Figs. 4 to 8, it will be seen that this panel 175 has a pair of rearwardly projecting ears 176 adjacent its upper corners which are pivoted on a rod 177 mounted in the same brackets 169 as the panel 170. A torsion spring 178 (Figs. 5, 7 and 8) is mounted on rod 177 in position to urge panel 175 normally into a retracted position, as shown in Fig. 7, when the hopper is closed.

Means are provided for causing panel 175 to swing forward against spring 178 when the hop-

per opens and for holding the panel in the resulting advanced position. Referring to Figs. 6, 7 and 8, two brackets 180 are welded or otherwise secured to the back of panel 175 at opposite sides of the frame. These brackets extend downwardly below panel 175, and each bracket is formed with a convexly curved rear edge 181 terminating at its upper end in a slot 182. The front edge of each bracket 180 is straight except for a slot 183 formed just below the lower edge of panel 175, as shown in Fig. 7.

The hopper tray 75 carries means for engaging brackets 180 to swing panel 175 forward when the hopper opens. Referring to Figs. 6 to 8, at either side of the hopper the tray flange 77 has welded or otherwise secured thereto an arm 185 including a forked outer end in which an upwardly extending lever 186 is pivotally mounted on a pin 187. A torsion spring 188 is arranged on pin 187 in position to urge lever 186 outwardly, i. e., counterclockwise as viewed in Figs. 7 and 8, and the lower end of the lever is turned over at 189 to engage a shoulder 190 on the fork 185 to limit this outward movement. At its upper end, each lever 186 carries a roller 191 of proper size to fit within the slots 182 in brackets 180.

The operation of these parts in moving panel 175 is illustrated in Figs. 6 to 8. When the hopper is closed, the panel is in the position shown in Fig. 7, and the rollers 191 on levers 186 ride against angle irons 192 secured to the rear pair of channel irons 27 as shown in Figs. 6 and 7. As the hopper starts to open, the tray 75 raises arms 185 and also moves them forward until the rollers 191 are in contact with the curved edges 181 of brackets 180. As the hopper continues to open, the levers 186 act through rollers 191 to swing the panel 175 forward, during which movement the rollers 191 ride up bracket edges 181 until they enter slots 182 as the hopper reaches its fully opened horizontal position, thus locking the panel 175 in forward position as shown in Figs. 2 and 8 and also in Fig. 4. It will also be seen in Fig. 8 that in these relative positions of the parts, the upwardly flared rear edge 180 of hopper tray 75 will enter the slots 183 at the front of brackets 180, as shown in Fig. 8, thus forming an interlock between the panel 175 and tray 75 effectively closing the interior of the unit as shown in Fig. 4.

It will thus be seen that these panels 88, 170 and 175 not only cooperate with the hopper to provide a smooth and finished appearance, but in addition they greatly facilitate the maintenance

of properly clean and sanitary conditions for the unit. When the hopper is closed, as shown particularly in Fig. 1, the smooth arrangement of the fixed and movable panels and the skirt 85 avoids the formation of pockets or crevices in which dust and dirt can collect and thus simplifies effective cleaning. The same is true of the cooperative action of panel 175 and the hopper tray 75, the panel serving as a splasher back when the hopper is open and thus both

shielding the interior of the unit and facilitating cleaning of the hopper when open. In addition, the flushing system as described and shown assures effective flushing of the bowl to assure sanitary conditions at all times.

A member such as a foot treadle 200 is provided for actuating the flushing valve 127, and this treadle is mounted for movement in response to opening movement of the hopper from a retracted and substantially inaccessible position 75 wherein it is inoperable to an advanced operat-

ing position where it is readily accessible. Referring particularly to Figs. 7 to 11, the treadle 200 is mounted on a carriage 201 which in turn is mounted for sliding movement on a pair of rails 202 supported in brackets 203 at the bottom of the frame 25. The treadle 200 is mounted for rocking movement in a vertical plane on a pin 204 which is carried by a vertical stud 205 mounted in the carriage 201, and a torsion spring 206 (Fig. 11) is arranged to urge stud 205 normally to a position in which the treadle 200 is substantially parallel to the rails 202 as shown in Fig. 10. A spring 207 is positioned between the treadle and carriage 201 to hold the treadle in a normally substantially level position, and a rubber button 208 is secured under the outer end of the treadle as a cushion for engaging the floor when the treadle is actuated.

The inner end of the treadle 200 is formed into an arm 210 which is adapted to engage a laterally extending trunnion 211 on one arm 212 of a bell crank lever pivotally mounted in a bracket 213 in the frame as shown in Figs. 9 and 10. The other arm 214 of this lever extends under the operating plunger 215 of the flushing valve 127 as shown in Fig. 11, the valve having been removed in Fig. 9 to show parts which would otherwise be concealed thereby. A spring 216 is positioned under lever arm 214 and substantially in line with the plunger 215 to hold the lever arm in contact with the plunger and thus to prevent chattering. It will be understood that when the treadle is depressed, its arm 210 will engage trunnion 211 and thus raise lever arm 212, which will in turn raise lever arm 214 against plunger 215 and thus open valve 127 to admit flushing water to the hopper bowl as described.

Referring to Fig. 10, it will be seen that the treadle 200 and lever arm 212 are so arranged that when the treadle is in position parallel with the rails 202, its arm portion 210 is laterally withdrawn and spaced from the trunnion 211 and cannot actuate the lever 212-214. Accordingly, means are provided for causing lateral swinging movement of the treadle as it reaches its outermost position in such manner as to bring its arm 210 into desired operating position under the trunnion 211. Referring to Figs. 9 and 10, the treadle includes a forked portion 220 which carries a roller 221 arranged on a vertical axis for contact with a cam 222 mounted on the inner brace plate 104 of the frame. This cam is of such configuration and so positioned in the frame, as shown in Figs. 9 and 10, that as the treadle approaches its outermost position, the roller 221 will engage the side of the cam and thus force the treadle to swing about the vertical axis of pin 205, in clockwise direction as viewed in Fig. 10, to a position in which its arm 210 engages under trunnion 211 as shown in Fig. 9. It will also be noted that this motion provides for swinging the outer end of the treadle out to a more convenient position for ready actuation than if the treadle remained at right angles to the frame and therefore partially covered by the open hopper bowl.

Means are provided for causing this movement of the treadle between its retracted and advanced position in response to the opening and closing movement of the hopper. Referring to Figs. 3 and 7 to 9, a sector 225 is welded or bolted to the bracket 99 at the side of the hopper adjacent the treadle, and this sector is provided with a curved outer flange 226 forming a drum for receiving a cable 227. One end of this cable passes through a flange 228 at one end of the sector 225 and is

secured to a spring 229. From this spring, the cable passes part way around the outer side of the sector and is then looped around a pulley 230 mounted in the frame adjacent the inner ends of rails 202. The cable is then fastened at 231 to a collar 232 loosely mounted on the vertical pivot stud 205 of treadle 200, the collar in turn being held on the stud by means such as a snap ring 234. From the collar 232, the cable is looped around another pulley 235 in a bracket 236 at the front of the frame, and finally back around the inner side of sector 225 through a flange 237 at the opposite end of the sector from flange 228, and its end is secured to a spring 238.

The operation of this treadle advancing and retracting mechanism is illustrated in Figs. 7 to 10. When the hopper is closed, the parts will be in the positions shown in Fig. 7, with the treadle retracted into the frame. When the hopper starts to open, the sector 225 rocks with the hopper about the axis of the trunnions 211, and the cable 227 will unwind from the outer side of the sector and simultaneously wind on the inner side of the sector. This will cause the part of the cable which is secured to collar 232 to move forwardly of the frame, thus carrying with it the stud 205 and hence the carriage 201 and treadle 200. During this movement, the springs 229 and 238 will keep the cable under tension, and the torsion spring 206 will tend to keep treadle 200 in line with the cable and rails 202 as shown in Fig. 10. However, as the treadle approaches its outermost position, the roller 221 will engage cam 222, forcing the treadle to swing about stud 205 and carrying its arm 210 under trunnion 211 as shown in Fig. 9 as the hopper reaches its open position. Thus with this construction, the treadle is not only retracted out of the way when the hopper is closed, but it cannot be actuated to open valve 127 except when it is in its advanced position, thus effectively preventing flushing and resulting waste of water except when the hopper is open.

It will be apparent that when this toilet unit is installed in a railroad car or other vehicle with its drain pipe 55 open to the atmosphere, the hopper bowl may be subjected to strong air currents, either inwardly or outwardly of the drain pipe, as a result of motion of the vehicle, and further as a result of changes in the air pressure within the car, particularly with certain types of air-conditioned cars which are affected by the opening of the doors or the like. Accordingly, means are provided for controlling passage through the discharge outlet 67, and for holding this outlet substantially closed against such air currents except during actual flushing operations. Thus as shown in Fig. 12, a flapper valve 240 is mounted for swinging movement at the back of the hopper bowl in position to overlie and substantially close the discharge outlet 67 when in the vertical position shown in full lines in Fig. 12. Means are also provided for causing the flapper valve 240 to swing into discharge pipe 10 and thus to open the discharge outlet when the hopper is flushed as shown in dotted lines in Fig. 12.

Referring to Figs. 13 and 14, it will be seen that the bracket frame 68 extends entirely across the back of the hopper bowl and is cut out at its center to encircle the discharge outlet 67. A rod 241 is journaled in this bracket frame to form a rock shaft to which flapper valve 240 is keyed or otherwise secured. Suitable packing may be provided for rod 241 if desired or necessary to assure against leakage. One end of rod 241 extends outwardly of bracket frame 68, and a lever arm 242

is clamped or otherwise secured thereto as shown in Fig. 14. One end of a Bowden wire 243 is secured to this lever 242, as by means of set screw 244, and the sheath 245 of this wire may be secured to bracket frame 68 by means such as a suitable clamp or clip 246. The wire 243 is looped loosely over the adjacent mechanism as shown in Fig. 3, and its other end is secured as shown in Fig. 9 to a clamp 247 carried by an extension portion 248 of the lever 214 which actuates the 10 plunger 215 of the flushing valve, the other end of the wire sheath 245 being clamped in the frame adjacent lever arm 214 as indicated in Fig. 9.

A dash pot 250 and spring 251 control movement of flapper valve 240. Referring to Fig. 14, 15 the dash pot 250 is carried by a bracket 252 secured in any suitable way to bracket frame 68. The spring 251 is mounted on a rod 253 slidably supported in bracket 252 and having its upper end pivoted to an arm or link 254 secured to rod 241. A member 255 is secured to rod 253 above spring 251 and is slotted to form a yoke straddling the upper end of the piston rod 256 of dash pot 250. The piston 257 is constructed with a check valve 258 arranged to permit rapid movement of the 25 piston downwardly in Fig. 14, in a direction compressing spring 251, but to retard return or upward movement of the piston.

It will be seen that with this construction, when the hopper is flushed by actuation of treadle 200, the lever arm 214 will force the Bowden wire 243 upwardly, thus forcing lever 242 to swing in clockwise direction as viewed in Fig. 14. This will in turn cause rod 241 and the flapper valve 240 to swing in the same direction, to the position of valve 240 shown in dotted lines in Fig. 14 in which it opens the discharge outlet 67 for free passage of the flushing water and other contents of the hopper. At the same time, link 254 will swing in the same direction and will force rod 253 and yoke 255 downwardly against spring 251 to compress the spring and to move piston 257 downwardly in the dash pot cylinder, the slotted construction of the yoke providing for the necessary relative angular movement of rod 253 and piston rod 256.

The flapper valve 240 will remain open so long as the treadle is depressed and flushing continues. Thereafter, when the treadle is released and lever arm 214 returns to its inactive position under the force of the usual spring in valve 127 for holding its plunger 215 in closed position, the spring 251 will expand and will force yoke 255 and rod 253 upwardly, thus acting through link 254 to rock rod 241 in the direction to close valve 240. This closing movement will be retarded by the action of dash pot 250, to prevent undue noise. It should be noted, however, that valve 240 is preferably not in tight sealing relation with the discharge outlet, thus permitting complete drainage of the bowl when the hopper is moved to its substantially vertical closed position.

Fig. 16 illustrates, as a modification, electric means for controlling the flapper valve 240 in response to actuation of the flushing means of the hopper. As shown, a solenoid 260 is mounted at the back of the pipe 70, and its plunger 261 is connected by means of a link 262 with the back of the flapper valve. A spring 263 is arranged to urge the plunger outwardly when the operating coil of the solenoid is deenergized, and thus to urge the flapper valve 240 to its position shown in dotted lines wherein it substantially closes the discharge outlet of the hopper. The flushing valve 127 is shown somewhat diagrammatically

as positioned with its plunger 215 arranged for direct actuation by a foot treadle 265 which is shown diagrammatically but corresponds in function and operation to the treadle 200, this treadle 265 being shown as fulcrumed on a bracket 266. A normally open electric switch 267 for controlling current to the operating coil of the solenoid 260 is positioned with its plunger 268 or other operating handle arranged to be engaged by the treadle 265. Preferably the switch 267 is of such construction that it will be closed as soon as its plunger 268 is moved inwardly, but with this plunger capable of continuing inward movement after the switch is closed.

With this construction, the plunger 268 is so arranged that it will close switch 267 as soon as the treadle 265 is actuated but before the treadle has pushed plunger 215 a sufficient distance to open valve 127. Accordingly, it will be seen that when the treadle is depressed to flush the hopper, it will close switch 267 and thus energize the solenoid 267 before it opens the flushing valve. As a result, the valve 240 will be opened by retraction of the solenoid plunger 261 before the flushing valve is opened, and similarly when the treadle is released, it will cause closing of the valve 127 before switch 267 is opened, thus providing for completing discharge of the flushing water from the hopper before solenoid 260 is deenergized and thus before flapper valve 240 is closed.

Figs. 17 and 22 show, as a further modification, hydraulic means for operating the flapper valve 240. A hydraulic cylinder 270 is connected by a pipe 271 to the main line 125 of flushing water ahead of the flush valve 127, thus connecting the interior of cylinder 270 directly to pressure in line 125 at all times. The piston within cylinder 270 is provided with a spring 272 of such characteristics that when full line pressure is applied within the cylinder, the spring will be overcome and the piston will be forced to its outermost position in which its piston rod 273 will force the flapper valve 240 to its position substantially closing the discharge outlet of the hopper. At the same time, this spring 272 is of such strength that when there is a drop in line pressure as a result of opening valve 127 to flush the hopper, it will move the piston inwardly of cylinder 270 and thus permit valve 240 to open. The piston rod 273 may be provided with a linked connection to valve 240 similar to that shown in Fig. 16, or the valve may be counterweighted in such manner as to open when the pressure of the piston rod against its rear side is removed.

With this construction, as shown in Fig. 17, when the treadle 275 is depressed to force valve plunger 215 upwardly and thus to open valve 127, flushing water will be admitted from the line 125 to the hopper, which will cause an immediate drop in line pressure effective within cylinder 270. As a result of this drop in pressure, the spring 272 will be able to move the piston inwardly of cylinder 270, and thus to cause opening of flapper valve 240. This condition will continue so long as the flushing operation, since the line pressure will remain reduced as long as the water is in motion past pipe 271. After flushing is completed and the treadle released, the valve 127 will close and will thus restore full line pressure in pipe 271 and cylinder 270, and this in turn will force the piston outwardly of the cylinder and so return valve 240 to its closed position.

Referring to Fig. 18, it will be apparent that

when the hopper moves between its open and closed positions, the pipe 70 which connects its discharge outlet with the main drain pipe 55 telescopes within pipe 55, and it is important to keep the connection between these two pipes substantially liquid tight to prevent leakage. Accordingly, means are provided for effectively sealing the joint between these two pipes while at the same time permitting not only free telescoping movement between them but also a limited degree of angular movement to allow for play in the pivotal mounting of the hopper itself. As shown in Fig. 18, the pipe 55 is Y-shaped at its upper end, with the pipe 70 entering the back of the Y and being capable of telescoping movement towards the front when the hopper closes, this front arm of pipe 55 being shown as provided with a removable cap 280 for ready cleaning of the pipe.

A flexible sealing member 281 such as a section of tubing of raw hide or like material is arranged to overlie the joint between the two pipes 70 and 55, and an annular coil spring 282 is superimposed on the sealing member 281 to hold it firmly in contact with the pipes. Since pipe 70 telescopes into pipe 55, this leaves the outer end 283 of pipe 55 forming a shoulder tending to limit movement in one direction of the spring 282 and sealing member 281 axially of the pipes. To limit movement of the sealing means in the opposite direction, a collar 285 is positioned to overlie the sealing member and spring, and the outer end of sealing member 281 is turned over outwardly within this collar as shown in Fig. 18. Two metal straps 286 are welded or otherwise secured at opposite sides of collar 285, and the lower end of each of these straps is formed into a pair of ears 287 providing a pivotal mounting for a link 288. The other end of each of these links 288 is anchored loosely in a bracket 289 welded or otherwise secured to the side of pipe 55. With this construction, and with the collar 285 mounted loosely on pipe 70 as stated, it will be seen that the collar is held against movement axially of the pipes but at the same time can wobble or float to a limited extent relative to either or both pipes, thus serving to hold the sealing member 281 and its spring 282 in proper position overlying the joint between these two pipes while still permitting relative angular movement of the pipes incident to opening and closing movement of the hopper.

Figs. 19 and 20 illustrate in detail the releasable latch mechanism for the lavatory. Each latch member 46 is carried by the outer end of one of a pair of rods 290 mounted for axial movement within the lavatory frame, and the handle 47 is pivotally mounted on the inner ends of these rods in a casing 291. Springs 292 are arranged as shown in Fig. 18 to urge the rods 290 normally outwardly to the locking position of latches 46. The inner end of each rod 290 is provided with a cam follower 293 and lock nut 294, the cam follower including an axially projecting finger 295 adapted to cooperate with a camming surface 296 formed on the adjacent portion of handle 47. A shield 297 is secured to handle 47 as shown in Fig. 19 to form a stop for the fingers of the user.

In operation, the normal position of these parts is as shown in Figs. 19 and 20, with springs 292 urging latches 46 outwardly into locking position. Outward movement of latches 46 and rods 290 is limited by contact between the finger 295 on each cam follower 293 and the handle 47. 75

When the handle is raised by the operator, it pivots in counterclockwise direction as viewed in Fig. 20, thus causing its camming surfaces 296 to move relative to fingers 295 and to urge followers 293 and rods 290 inwardly. This in turn causes latches 46 to be retracted to unlocked position and permits the lavatory to open. When the lavatory is closed, the camming surface 298 of latches 46 engage the sides of the frame and thus cause the latches to retract sufficiently to enter the frame after which springs 292 return them to locked position.

Fig. 22 shows a modified arrangement of piping suitable for use in the toilet unit of the invention as described and shown in Figs. 1 to 21. As already pointed out, the piping diagram in Fig. 22 includes a hydraulic cylinder 270 for controlling the flapper valve at the discharge outlet of the hopper, this cylinder being connected through pipe 271 directly with the main line 125 of flushing water ahead of the flush valve 127, which is connected to line 125 by a pipe 126 in the same manner as already described and shown. The valve 127 also is connected as shown in Fig. 21 by a pipe 128 with the vacuum breaker 129, but the connection from the vacuum breaker to the jet fixture 110 is provided by a pipe 300 and a flexible hose 301 in place of the swiveled coupling 131 in Fig. 21 to allow for opening and closing movement of the hopper relative to pipe 300.

Fig. 22 also shows a modified arrangement for controlling the flow of water to and from the hydraulic cylinders 140 which open and close the hopper. The pipe 303 is arranged to supply cold water to the lavatory faucet, and a branch pipe 304 leads from pipe 303 to a four-way valve 305 shown as provided with a sliding control member 306. One pipe 310 leading from valve 305 is connected by means of flexible hoses 311 with the lower sides of the hydraulic cylinders 140. Another pipe 312 leads from the valve 305 and connects through flexible hoses 313 with the upper sides of the cylinders 140. The fourth pipe 315 from valve 305 leads to a reservoir 316 positioned substantially above the plane of the hopper. This reservoir is in turn connected through a pipe 317 with a valve 320 provided with an operating button 321 and connected by a flexible hose 322 with one of the shower ring pipes 120, the pipe 317 being provided with a suitable one-way valve 323 to prevent the upward flow of water therethrough. An overflow pipe 324 leads from the reservoir 316 to the discharge tank of the lavatory, which is indicated diagrammatically at 325 and corresponds in function to the tank 51 in Fig. 2.

In the operation of this piping arrangement, when the valve lever 306 is moved to its "Open" position, it will connect pipe 303 with pipe 310 leading to the lower sides of the cylinders 140 and at the same time will connect the upper sides of cylinders 140 through the pipes 312 and 315 to the reservoir 316. This will cause the hopper to open, and at the same time will cause waste water from the cylinder 340 to be conducted to the reservoir 316. The valve 320 is so positioned in the frame that its operating button 321 will be engaged and moved to open position by the hopper as it reaches its own horizontal open position, for example during the last approximately 8° of the hopper movement. As a result, the waste water which has been forced up into reservoir 316 will flow through pipe 317, valve 320 and hose 322 into the shower ring pipe 120 and thence into the hopper bowl to provide the de-

stred preliminary flush or wet bowl. When the valve control member 306 is moved to its "Close" position, the converse operation takes place, with the hopper being closed and the waste water from the lower sides of cylinders 140 being similarly forced through the pipe 315 to the reservoir 316. This water will thus be collected in the reservoir for the next opening movement of the hopper, and any excess water in the reservoir will be removed through the overflow pipe 324 to drain tank 325 and thence to the main drain of the unit. The valve 323 prevents water from traveling up pipe 317 to reservoir 325 during flushing of the hopper.

Figs. 1 and 2 illustrate an arrangement of light sources 36 and 37 for the mirror 35 to provide effective illumination on the face of the user without direct glare in the user's eyes. The frame 26 includes housings 330 and 331 for light sources which are positioned respectively above and below mirror 35 and extend forwardly of the vertical plane of the mirror. These housings are located in predetermined positions which are correlated with visibility characteristics of the eyes of the normal user so that adequate light is produced and cast upon the face of the user, but direct glare is effectively avoided. This is accomplished through utilization of the fact that with the eyes looking straight ahead, the normal range of vision or perception of lighted objects extends over a considerably greater angle in a horizontal plane than it does in a vertical plane. In accordance with the present invention there are no light sources at the sides of the mirror within the normal wide horizontal range of vision, and hence no glare is produced in the eyes of the user. The light sources are confined to the areas above and below the mirror and are located in such positions that they are primarily beyond or outside the range where full visibility occurs, either as viewed directly or by reflection in the mirror, and yet are so arranged as to project light directly upon the face of the user to give good illumination thereof.

Referring to Fig. 2, the housing 330 above the mirror has a panel 333 removably secured thereto as by means of bolts 332, and this panel carries brackets 334 forming a mounting for a fluorescent tube 335 arranged substantially horizontally within the housing. A reflector 336 is secured to panel 333 within the housing for directing light from the tube 335 generally downwardly, and the panel is cut out to receive a plate 337 of frosted glass or other suitable translucent material arranged in position to transmit the light from tube 335 and reflector 336 downwardly and forwardly of the mirror. In addition, as shown in Fig. 2, the panel 333 is so formed that its lower portion and the plate 337 are arranged to slope upwardly away from the mirror at an angle of somewhat less than 45° to the horizontal, for example an angle of 30°. With this arrangement the light from tube 335 will be directed forwardly of the mirror and downwardly at angles of the order of substantially 60° to the horizontal, as indicated by the dotted lines in Fig. 2, and will thus effectively illuminate the face of the user of the mirror from above but will not pass directly to the user's eyes, as is illustrated by the fragmentary showing of the figure of a user in Fig. 2.

It will be noted that the tube 335 and all of its associated parts within housing 330 are supported by panel 333, thus substantially simplifying showing of this part of the unit. With this

arrangement, it is necessary only to unscrew bolts 332, and the panel may then be removed for ready access to the tube. Also, a socket 338 of the usual type is mounted in the panel 333 for receiving the plug of an electric shaver or other appliance for use in conjunction with the mirror, this socket being similarly removable from the frame with panel 333.

The housing 331 below the mirror is equipped to suit a suitable bracket 339 for mounting a fluorescent tube 340 in substantially horizontal arrangement, and a reflector 341 is provided for directing the light from the tube forwardly from the mirror and upwardly. The housing 331 is open at the front and is provided with a hinged panel 342 carrying a diffusing plate 343, and this panel and plate are arranged to slope downwardly away from the plane of the mirror at an angle of more than 45° to the horizontal, for example an angle of 60°. This arrangement of the reflector and the diffusing plate provide for directing the light from the fluorescent tube 340 forwardly of the mirror and upwardly at angles of the order of substantially 30° to the horizontal, as indicated by the dotted lines in Fig. 2, it having been found that light directed in this manner will effectively illuminate the lower part of the face of the user of the mirror without impinging directly on the user's eyes, as illustrated in Fig. 2. In addition, it will be apparent that if light rays from either of tubes 335 and 340 fall directly on the mirror, their angles of incidence will be such that they will be reflected well outside of the normal range of vision of the user, thus effectively preventing reflected glare.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A folding toilet of the character described comprising, a frame, a hopper, means supporting said hopper for swinging movement in said frame between an open horizontal position and a closed substantially vertical position, operating mechanism for said hopper in said frame, a panel adapted to conceal said operating mechanism, and means operatively connecting said panel and hopper to cause movement of said panel to said concealing position in response to closing movement of said hopper and to cause movement of said panel from said concealing position to a position out of the way of said hopper in response to opening movement of said hopper.

2. A folding toilet of the character described comprising a frame, a hopper, means supporting said hopper in said frame for swinging movement between a substantially horizontal open position and a substantially vertical closed position, a panel mounted for swinging movement in said frame above said hopper, and means carried by said hopper for swinging said panel forward upon opening movement of said hopper to shield the area in said frame above the back of said open hopper.

3. A folding toilet unit of the character described comprising a frame, a hopper mounted in said frame for swinging movement between a substantially horizontal open position and a substantially vertical closed position, power operated means within said frame for effecting said swinging movement of said hopper, a panel

mounted in said frame for swinging movement in the space directly above said hopper between a retracted position out of the way of said hopper when closed and an advanced position above the back of said hopper for shielding the interior of said frame, means responsive to opening movement of said hopper for causing movement of said panel to said advanced position, and control means accessible exteriorly of said frame for actuating said power operated means.

4. A folding toilet unit of the character described comprising a frame, a hopper mounted in said frame for swinging movement between an open position ready for use and a closed position, a hydraulic cylinder arranged to effect said movement of said hopper upon the selective application of pressure liquid thereto, means for connecting said cylinder to a source of liquid under pressure, and means under control of the user for selectively controlling the flow of said liquid to said cylinder to effect said movement of said hopper.

5. A folding toilet of the character described comprising a hopper, means supporting said hopper for movement between an open position ready for use and a closed position, hydraulic means for effecting said movement of said hopper, and means for conducting waste liquid from said hydraulic means to said hopper to provide a wet bowl therein when said hopper is in said open position.

6. A folding toilet of the character described comprising a frame, a hopper supported in said frame for movement between an open position for use and a closed position, a double-acting hydraulic cylinder for effecting the movement of said hopper, means forming an inlet for flushing liquid to said hopper, and means for selectively connecting one side of said cylinder with a source of liquid under pressure and for simultaneously connecting the opposite side of said cylinder with said flushing inlet to cause waste liquid from said cylinder to be conducted to said hopper inlet means to provide a wet bowl therein while said hopper moves to said open position.

7. A folding toilet of the character described comprising a hopper, means supporting said hopper for movement between an open position ready for use and a closed position, hydraulic means for effecting said movement of said hopper, a reservoir, means for selectively connecting said hydraulic means with a source of liquid under pressure, means for conducting the discharge of said hydraulic means to said reservoir to cause waste liquid therefrom to be conducted to said reservoir, and means providing a connection from said reservoir to said hopper to conduct said liquid from said reservoir to said hopper to provide a wet bowl therein when said hopper is in said open position.

8. A folding toilet of the character described comprising a hopper, means supporting said hopper for movement between an open position ready for use and a closed position, a hydraulic cylinder for effecting said movement of said hopper, a reservoir located above the level of said hopper, means for connecting said cylinder with a source of liquid under pressure, means for connecting the discharge of said cylinder with said reservoir to cause waste liquid from said cylinder to be conducted to said reservoir, a conduit connecting said reservoir with said hopper, a valve controlling said conduit, and means responsive to movement of said hopper

from said closed position to said open position for operating said valve to admit liquid from said reservoir to said hopper to provide a wet bowl therein when said hopper is in said open position.

5 9. A folding toilet unit of the character described comprising a frame, a hopper mounted in said frame for swinging movement between a substantially horizontal open position and a substantially vertical closed position, means including a normally closed valve for flushing said hopper, a treadle for operating said valve, means supporting said treadle for sliding movement between a retracted position and an advanced position, and means responsive to said opening and closing movement of said hopper to effect said sliding movement of said treadle respectively between said advanced position and said retracted position.

10 10. A folding toilet unit of the character described comprising a frame, a hopper mounted in said frame for swinging movement between a substantially horizontal open position and a substantially vertical closed position, means including a normally closed valve for flushing said hopper, a treadle for operating said valve, means supporting said treadle for movement between a retracted position and an advanced position, means responsive to said opening and closing movement of said hopper to effect the movement of said treadle respectively to and from said advanced position, means defining an operative position for said treadle angularly spaced from the position thereof during the major portion of said movement, and means effective as said treadle approaches said advanced position to cause angular movement of said treadle into said operative position.

25 11. A toilet unit of the character described comprising a frame, a hopper mounted in said frame for swinging movement between a substantially horizontal open position and a substantially vertical closed position said hopper having a discharge outlet, a flapper valve for controlling the passage of air currents through said outlet, means for flushing said hopper upwardly through said outlet, means normally maintaining said flapper valve in position substantially closing said outlet, and means effective in response to actuation of said flushing 30 means for causing movement of said flapper valve to a position opening said outlet.

45 12. A toilet unit of the character described comprising a frame, a hopper mounted in said frame for swinging movement between a substantially horizontal open position and a substantially vertical closed position, said hopper including a bowl having a discharge outlet positioned above the bottom level thereof, a valve mounted for swinging movement between a position substantially closing said outlet and an open 50 position providing for free discharge through said outlet, releasable means for maintaining said valve in said closing position, the bottom of said bowl sloping upwardly to said outlet, 55 means for flushing said hopper upwardly through said outlet, and means responsive to actuation of said flushing means for effecting the release of said releasable means to provide for swinging movement of said valve to said open position.

60 13. A toilet unit of the character described comprising a frame, a hopper mounted in said frame for swinging movement between a substantially horizontal open position and a substantially vertical closed position, said hopper 65

including a bowl having a discharge outlet positioned above the bottom level thereof, a valve for controlling the passage of air currents through said outlet, the bottom of said bowl sloping upwardly to said outlet, means including a member under the control of the operator for flushing said hopper upwardly through said outlet, and means operatively connecting said member and said valve to cause opening movement of said valve when said member is actuated to initiate flushing of said hopper.

14. A toilet unit of the character described comprising a frame, a hopper mounted in said frame for swinging movement between a substantially horizontal open position and a substantially vertical closed position, said hopper including a bowl having a discharge outlet positioned above the bottom level thereof, a valve for controlling the passage of air current through said outlet, the bottom of said bowl sloping upwardly to said outlet, means including a member under the control of the operator for flushing said hopper upwardly through said outlet, and means mechanically connecting said member and said valve for causing opening movement of said valve in response to actuation of said flushing means.

15. A toilet unit of the character described comprising a frame, a hopper mounted in said frame and including a bowl, said hopper having a discharge outlet positioned above the bottom level of said bowl, a valve for controlling the passage of air currents through said outlet, the bottom of said bowl sloping upwardly to said outlet, means for flushing said hopper upwardly through said outlet, electrically operated means normally maintaining said valve in position substantially closing said outlet, and control means for said electrically operated means responsive to operation of said flushing means to cause opening movement of said valve.

16. A toilet unit of the character described comprising a frame, a hopper supported in said frame and having a discharge outlet, a valve for controlling said outlet, releasable hydraulic means for normally maintaining said valve in position substantially closing said outlet, means for flushing said hopper, means for connecting said hydraulic means and said flushing means to a common source of liquid under pressure, and means in said hydraulic means effective in response to a drop in line pressure upon operation of said flushing means to release said valve.

17. A toilet unit of the character described comprising a hopper including a bowl having a bottom and side portions, said hopper having a discharge outlet at the back of said bottom portion, said bottom portion of said bowl being arranged to slope upwardly from the front to said discharge outlet, means forming an inlet aperture for flushing liquid positioned adjacent the front of said bottom portion and directed towards said discharge outlet, said aperture being positioned below the level of said outlet and extending across a substantial proportion of the width of said bottom portion but being of substantially lesser dimensions in the direction perpendicular to said bottom portion, and means for connecting said inlet aperture with a source of liquid under pressure to provide a broad and relatively flat jet of liquid directed across said bottom portion to sweep the contents of said hopper upwardly towards said discharge outlet.

18. A toilet unit of the character described

comprising a hopper mounted for swinging movement between a substantially horizontal open position and a substantially vertical closed position, said hopper including a bowl having a bottom and side portions, said bottom being arranged to slope upwardly from front to back when said hopper is in open position, means forming a discharge outlet for said hopper adjacent the back of said hopper bottom, means for conducting flushing liquid under pressure to said hopper, and means forming an inlet aperture for said flushing liquid positioned opposite said outlet and adjacent the front of said hopper bottom, said aperture being elongated across the width of said hopper bottom and being located below the level of said discharge outlet in the open position of said hopper to provide a broad and relatively flat jet of said flushing liquid directed across said hopper bottom to sweep the contents of said hopper upwardly towards said discharge outlet.

19. A folding toilet unit of the character described comprising a frame, a hopper mounted in said frame for swinging movement between a substantially horizontal open position and a substantially vertical closed position, means including a normally closed valve for flushing said hopper, a treadle for operating said valve, means supporting said treadle for sliding movement between a retracted position and an advanced position, means responsive to said opening and closing movement of said hopper to effect said sliding movement of said treadle respectively between said advanced position and said retracted position, means separate from said valve for admitting flushing liquid to said hopper, and means responsive to movement of said hopper from said closed position to said open position for actuating said independent means to admit a predetermined limited quantity of flushing liquid to said hopper to provide a wet bowl therein.

20. A folding toilet unit of the character described comprising a frame, a hopper mounted in said frame for swinging movement between a substantially horizontal open position and a substantially vertical closed position, said hopper including a bowl having a discharge outlet positioned at the back thereof, a flapper valve controlling said outlet, means responsive to movement of said hopper from said closed position to said open position for admitting a predetermined limited quantity of flushing liquid to said hopper to provide a wet bowl therein in said open position thereof, means normally maintaining said flapper valve in position substantially closing said outlet to maintain said wet bowl, means operative in said open position of said hopper for flushing said bowl, and means responsive to actuation of said flushing means for causing movement of said flapper valve to a position opening said outlet.

21. A folding toilet unit of the character described comprising a hopper, mounted for swinging movement between an open horizontal position and a substantially vertical closed position, said hopper including a bowl having a discharge outlet positioned at the back thereof and having the bottom thereof arranged to slope upwardly from the front to said discharge outlet, a flapper valve controlling said outlet, means normally maintaining said flapper valve in position substantially closing said outlet, means forming an inlet aperture for flushing liquid positioned adjacent the front of said bowl and directed towards said discharge outlet, said aperture being

elongated across the width of said bowl to provide a broad and relatively flat jet of liquid directed across the bottom of said bowl to sweep the contents of said hopper towards said discharge outlet, means including a valve operative in said open position of said hopper for supplying flushing liquid to said jet aperture, and means responsive to actuation of said liquid supplying means for causing movement of said flapper valve to a position opening said outlet. 10
